G. W. WHITE.

ROTARY CYLINDER FURNACE.

No. 248,000.

Patented Oct. 4, 1881.

UNITED STATES PATENT OFFICE.

GEORGE W. WHITE, OF SAN FRANCISCO, CALIFORNIA.

ROTARY-CYLINDER FURNACE.

SPECIFICATION forming part of Letters Patent No. 248,000, dated October 4, 1881.

Application filed August 24, 1877.

To all whom it may concern:

Be it known that I, GEORGE W. WHITE, of the city and county of San Francisco, and State of California, have invented Improvements in 5 Rotary-Cylinder Furnaces; and I do hereby declare the following to be a full, clear, and exact description thereof, reference being had to the accompanying drawings.

My invention relates to certain improvements upon the rotary-cylinder furnace for which Letters Patent No. 44,145, dated September 6, 1864, and No. 46,287, dated February 7, 1865, were issued to me. The furnace described in said patents consisted of a hollow cylinder mounted upon suitable pulley-bearings in an inclined position. The fire-place or furnace was so placed that the heat and products of combustion were directed into and passed through the cylinder, while the ore 10 was fed into its upper end, the rotation of the cylinder, combined with certain projections on its interior, causing the ore to travel toward its lower or discharge end, and at the same time the projections served to alternately lift 15 and drop the ore through the passing heat, the whole forming a simple and complete system for roasting ores. In the first-named patent above referred to the fire-place or furnace was placed at the upper or receiving end of the cylinder and the ore passed down the incline in 20 the same direction that the heat and products of combustion traveled, while in the latter-named patent the furnace or fire-place was located at the lower end of the cylinder and the ore was introduced at the upper end, so that 25 the ore was compelled to travel against the heat. The latter furnace was constructed with a central flue, through which the heat and products of combustion passed, and a series of 30 parallel flues surrounding the central flue, through which the ore passed in being reduced.

My present invention consists, first, of an arrangement by which I am enabled to shift the furnace to either inclination and feed the ore 35 in either direction; second, to the arrangement of parallel flues inside the cylinder around the main flue, which serve as connecting-flues between the fire-place and chimney, and through 40 which the heat and products of combustion from the furnace are conveyed to the chimney, while the ore passes through the center or main flue and out of contact with the draft and pro-

ducts of combustion from the fire-place, thus converting the furnace into a muffle, which adapts it for reducing that class of ores from 55 which it is desired to expel metallic vapors, and from which it is desired to exclude the products of combustion during the reducing process.

Referring to the accompanying drawings, 60 Figure 1 is a perspective of a furnace with my improvements attached. Fig. 2 is a sectional view through *z z* of Fig. 4. Fig. 3 is a section on line *y y* of Fig. 4. Fig. 4 is a longitudinal section of the furnace.

In my present construction of the furnace I 65 mount the cylinder *A*, fire-place or furnace *B*, and receiving-box *C* upon a single platform, *D*. The furnace or fire-place *B* is placed at one end of the platform and the receiving-box 70 *C* at the opposite end, while the rotating cylinder *A* is mounted upon suitable supporting-pulleys between them, so that its ends pass through openings in their sides, as represented. A feed-hopper, *E*, is placed upon the furnace 75 *B*, and a conducting-tube, *f*, extends from its lower end downward into the open end of the cylinder. Another hopper, *G*, is placed above the receiving-chamber *C*, at the opposite end of the cylinder, and a tube, *h*, connects its lower 80 end with the interior of the inner cylinder, so that the ore can be fed to either end of the cylinder, as desired.

b is the chimney or flue through which the draft from the fire-place *B* passes out into the 85 open air. This chimney-flue is made large enough around the inner cylinder, *K*, to prevent being choked. The inner cylinder, *K*, of my present furnace projects beyond the outer cylinder and outer flues, *l*, at the end next to 90 the chamber *C*. The outer flues are thus made to open into the chimney-flue *b*, through which the draft from the fire passes into the open air, while the ore is carried by the elongation of the central flue, *K*, across the chimney and 95 emptied into the receiving-chamber *C* without coming in contact with the draft from the fire-furnace. This is an important feature of the furnace, as among other evils existing in ordinary furnaces for roasting pulverized ores, 100 the products of combustion and draft from the fire-places pass through the ore-roasting chambers, and the draft is necessarily so strong that it carries with it a large percentage of the most

finely pulverized ore. As the ore is roasted when it enters the receiving-chamber C it is evident that the chamber C may be a mere open uninclosed space. It is enough that the central ore-flue, K, carries the ore beyond the chimney, so that the ore will be roasted and deposited without coming in contact with the draft, and products of combustion which come from the fire-furnace B pass through the outer flue, l, and out of the chimney b.

The platform D has a V-shaped ridge, i, across its middle on its under side, and this ridge rests upon and is secured to a sub-platform, J, so that the entire furnace can be tilted 15 upon this ridge to incline in either direction, according to the direction in which it is desired to feed the ore through the cylinder, or it may be mounted upon trunnions, as most convenient.

20 The cylinder A is constructed with a large central flue or passage, K, and a series of surrounding flues or passages, l. To make this cylinder, I take two concentric cylinders, the outer one of which forms the main or outside cylinder, while the inner one is considerably smaller in diameter than the outer one. This inner cylinder I support in position by means of parallel partitions m, which extend longitudinally the entire length of the cylinders 25 and between them, so that the space between each two partitions will form a heat flue or passage; or the inside cylinder may be made in longitudinal sections and secured in position by any suitable means.

30 35 In my former patents I described and claimed a plan of constructing the interior of the cylinder with longitudinal ridges, projections, or ribs placed at intervals apart, which ridges, projections, or ribs served to alternately raise 40 and drop the ore as the cylinder rotated.

The usual manner of forming the ridges, projections, or ribs was to form a lining of fire-brick on the inside of the cylinder, and place every third or fourth row of bricks endwise, so 45 as to form the projections described. In applying this inside cylinder to one of those old furnaces, therefore, I can simply place the inside cylinder inside of these projecting rows, so that they will form the partitions and out- 50 side passages or flues. The inside cylinder I provide with longitudinal ribs, projections, or recesses o, for lifting and dropping the ore in the same manner as when a single cylinder is used. In this furnace the ore will be fed into 55 the central or main flue, while the heat and products of combustion enter and pass through the surrounding flues or passages, thus heating up the ore-flue without direct contact of the flame with the ore.

60 65 65 By this method a much better concentration of heat upon the ore is obtained, and at a less cost of fuel, than when the heat passes through the central flue and the ore through the outer flues. The operation of one large central flue for the treatment of the ore is also much superior to the combined operation of the series of ore-flues shown in my former patent.

By this construction I obtain a furnace possessing the following advantages:

First. By tipping the furnace, ore may be fed through it, so as to pass while being reduced in the same direction that the heat passes, or in the opposite direction, as may be desired, and as may be best for the particular quality of ore being treated. 75

Second. The fire and heat surrounds the main flue in which the ore is treated, and thereby furnishes a better heat with less fuel than can be obtained in rotary furnaces not so constructed. 80

Third. The draft and products of combustion do not pass through the main flue or in contact with the ore.

I am aware that in the process of Charles William Siemens for manufacturing cast-steel 85 a rotary furnace was used in combination with a melting-furnace, and that such rotary furnace had a double series of concentric tubes running parallel with a main central flue, through which the ore passed; but in that rotary furnace the series of concentric flues did not open into a fire-chamber, but were of a peculiar construction and combination for the purpose of utilizing gases arising from the reducing process and hot air. These only supplied a small part of the heat for the furnace. The principal heat was obtained by burning fuel mixed with the ore in the central flue. The main fire being in the central flue where the ore was being roasted necessitated the 90 passing of a draft through that flue, which is not done in my furnace.

Having thus described my invention, what I claim, and desire to secure by Letters Patent, is—

1. The rotary cylinder A, furnace B, and receiving-box C, in combination with the platform having a central bearing, whereby they can be tilted to either inclination, substantially as set forth. 105

2. The combination, in a rotary-cylinder furnace, of the outside cylinder, A, provided with its flues l, and the inside cylinder, K, provided with open ends, with the furnace B, constructed as described, chamber C, and duplex feeding devices E G, whereby the ores are made to pass in either direction through a central rotating flue, while the heat and product of combustion are conducted through flues or passages which surround the ore-flue, 115 and out of contact with the ore, as set forth. 120

3. In a rotary-cylinder furnace, the combination of a central ore-flue with a series of concentric fire-flues, through which the draft and products of combustion pass from the fire-place to the chimney b direct without coming in contact with the ore, all constructed and operating substantially as herein described. 125

4. In a rotary-cylinder furnace, the combination of an extended inner ore-cylinder and ore-receiving chamber, C, with the shorter outer concentric flues, l, and the draft-chimney b, constructed and operating substantially as herein described. 130

5. The combination of the fire-furnace B, the rotating cylinder A, having the central ore-flue, K, the fire and draft flues l, with the receiving-chamber C, and chimney b, all constructed and operating substantially as herein described.

6. The combination, in a rotary-cylinder furnace, of the fire-furnace B, the outer concentric flues, l, the chimney b, and the central ore-chamber, K, with a feeding device, that the

ore being roasted will not come in contact with the draft or products of combustion from the fire-place B, substantially as herein described.

In witness whereof I have hereunto set my hand and seal.

GEO. W. WHITE. [L. S.]
